UNITED STATES PATENT OFFICE

2,143,100

BLOWER

Edward L. Anderson, Grosse Ile, Mich., assignor
to American Blower Corporation, Detroit, Mich.,
a corporation of Delaware

Application April 19, 1937, Serial No. 137,678

12 Claims. (Cl. 230—114)

My invention relates to fans and in particular to a means of controlling a volume of air and the movement of the air through the fan in order to insure the maximum efficiency of the fan at varying volumes.

It is my object to regulate the quantity of the air, at the same time using a regulating means as a means of guiding the air, so the variation in quantity of air will not disturb the efficiency of the fan for the volume being handled.

It is my particular object to provide a fan of the type having an axial entry and a radial peripheral delivery of the air with a Venturi shaped passageway to the fan, with which is associated a conical slidable inlet damper that reciprocates to and from and within the Venturi shaped conical inlet passageway.

It is my further object to provide in association therewith a plurality of arcuate axially disposed radially arranged guide vanes so as to guide the entering air between the sliding damper and the volute passageway through the passageway and to cause it to take a preliminary whirl when entering the fan.

It is my further object to arrange these vanes so that they can be adjustably positioned within the rotor of the fan.

Referring to the drawing:

Figure 1 is a side elevation of the fan showing one of the sides through which the air enters and showing the end of the slidable damper. The drive shaft is in section and the adjusting mechanism for the damper has been removed for the purpose of clarity.

Figure 2 is a section of the line 2—2 looking in the direction of the arrows, on Figure 1.

Figure 3 is a section of the line 3—3 looking in the direction of the arrows, of Figure 2.

Figure 4 is a view similar to Figure 2 showing the damper adjusting mechanism in its innermost position.

Figure 5 is a detailed view showing the overlapping relationship between the Venturi shaped conical inlet casing and the fan shroud mounted on each end of the fan blades.

Referring to the drawing in detail, 1 is a volute casing having oppositely distributed inlet openings in which are mounted conical Venturi shaped passageways 2 within the side walls 3.

50 The inner ends of these inlet passageways are arcuate in section, as at 4, and are in spaced parallel relationship with the throat 5 within the fan shroud 6 mounted on the plates 1. These plates are supported by the center plate 8, which is, in turn, mounted on the hub 9. This hub is

mounted on the shaft 10, suitably supported by the bearings 11. 12a indicates the outlet from the same.

Each of the inlet passageways 2 are provided with conical dampers that are disk like, designated 12. These dampers are mounted upon sliding hub 13 upon the drive shaft 10. The arms 13a position the damper 12 on the hub 13. They are connected by any suitable means to an adjusting means such as the rack 14 and the pins 15 actuated by the handle 16. These conical dampers 12 carry a plurality of radially arranged axially disposed arcuate inlet air guide vanes 17 which are arranged to slide with the damper 12 and with the hub 13 so that they may be adjusted to different positions within the fan.

The entering air is controlled in volume by the space between the inlet passageway 2 and the damper 12. The preliminary rotation of the air and the extent to which the rotating air is introduced into the fan is determined by the position of the guide vanes 17, which are known herein as the entry guide vanes.

The efficiency of the fan is maintained, to a large degree, and under some circumstances is increased by the entry guide vanes 17, because as the volume of air is reduced, the entry guide vanes are introduced further within the fan, and therefore give to the fan air that has already had a marked preliminary whirl, so as to increase the efficiency of the fan by supplying air with a preliminary whirl over a greater area of the plate 7.

In this manner, by simultaneously adjusting the volume and the extent in area over which the air with a preliminary whirl is delivered to the fan, the fan is enabled to operate at approximately the same efficiency on varying volumes.

This arrangement is facilitated by the overlapping of the Venturi shaped passageway 2 and the fan shrouds as shown in detail in Figure 5, because this provides for reentry air through the space between the parts 4 and 5, thereby insuring the distribution, not only of the reentry air but of the incoming air, particularly the incoming air with a preliminary whirl, over the entry ends of the fan blades, where it ordinarily would not pass, due to the dead air space that would otherwise exist, and due to the turbulent air that would exist on the outer end of the fan blades. 50 All of the several parts perform and relatively function in combination with one another in a modified relationship, as their operation is modified one by the other.

It will be understood that I desire to compre- 55

hend within my invention such modifications as may be clearly embraced within the claims and scope of my invention.

Having thus fully described my invention, 5 what I claim as new and desire to secure by Letters Patent is:

1. In a fan, the combination of a fan casing having an air entry passageway, a fan rotor axially disposed with respect to said passageway 10 and having blades spaced radially from the axis of rotation thereof, a disk like damper movable inwardly and outwardly with respect to said inlet passageway to control the volume of air passing therethrough, and entry guide vanes associated with said damper adapted to extend into said entry passageway and within the fan blades for giving a preliminary whirl to the entering air prior to entering the fan rotor.
2. In a fan, the combination of a fan casing 20 having an air entry passageway, a fan rotor axially disposed with respect to said passageway and having blades spaced radially from the fan axis, a disk like damper movable inwardly and outwardly with respect to said inlet passageway to control the volume of air passing therethrough, and entry guide vanes associated with said damper adapted to extend into said entry passageway and extensible within the fan blades for giving a preliminary whirl to the entering air prior to entering the fan rotor, said damper being conical in section.
3. In a fan, the combination of a fan casing 30 having a Venturi-shaped air entry passageway, a fan rotor axially disposed with respect to said passageway, a disk like damper movable inwardly and outwardly with respect to said inlet passageway to control the volume of air passing therethrough, and entry guide vanes associated with said damper adapted to telescopically extend into said entry passageway and fan rotor for giving a preliminary whirl to the entering air prior to entering the fan rotor, said damper being conical in section with a portion of its wall parallel to a portion of the wall of the Venturi-shaped entry passageway.
4. In a fan, the combination of a fan casing 40 having a conical entry passageway for incoming air with an inner Venturi-shaped throat, a fan rotor with radially outwardly shaped blades and axially disposed with respect to said entry passageway and adapted to introduce air into the interior of the rotor to deliver it peripherally, and a reciprocating conical damper with a plurality of longitudinally disposed inwardly extending guide vanes extensible telescopically within the fan blades and adapted to be adjustably positioned with the damper within said entry passageway and said rotor to impart a preliminary whirl to the air.
5. In a fan, the combination of a fan casing 50 having a conical entry passageway for incoming air with an inner Venturi-shaped throat, a fan rotor axially disposed with respect to said entry passageway having radially outwardly spaced blades and adapted to introduce air into the interior of the rotor to deliver it peripherally, and a reciprocating conical damper plate with a plurality of longitudinally disposed guide vanes adapted to be adjustably positioned with the damper plate within said entry passageway and extensible within the blades of said rotor to impart a preliminary whirl to the air, said entry guide vanes being arcuate in section.
6. In a fan, the combination of a fan casing 55 having a conical entry passageway for incoming air with an inner Venturi-shaped throat, a fan rotor axially disposed with respect to said entry passageway and adapted to introduce air into the interior of the rotor to deliver it peripherally, and a reciprocating conical damper with a plurality of longitudinally disposed guide vanes adapted to be adjustably positioned with the damper within said entry passageway and said fan rotor to impart a preliminary whirl to the air, said entry guide vanes being arcuate in section and equi-distantly and radially disposed with respect to the axis of the rotor.
7. In combination, a fan housing having oppositely disposed conical entry passageways, a fan rotor axially disposed therebetween, conical dampers adjustably positioned with respect to said entry passageways on either side thereof, and entry guide vanes longitudinally disposed 20 and movable with said dampers adapted to be positioned variably within said entry passageways and within said fan rotor.
8. In combination, a fan casing, a fan rotor having a plurality of arcuate peripheral blades 25 with their shrouds having inner arcuate ends, a conical inlet passageway having a Venturi-shaped inner end arranged in spaced parallel relationship within the arcuate end of said shrouds to form a reentry air passageway and a disk like 30 damper for said passageway carrying a plurality of longitudinally disposed guide vanes adapted to be positioned at varying positions within said inlet passageway rotor and reentry passageway.
9. A new article of manufacture for use with 35 fans comprising a conical inlet damper plate and a plurality of longitudinally disposed radially directed arcuate entry guide vanes, and means for adjustably positioning said mechanism within the air entry passageway of a fan for extension of 40 the entry guide vanes within the rotor of the fan.
10. A new article of manufacture for use with 45 fans comprising a conical inlet damper and a plurality of longitudinally disposed radially directed arcuate entry guide vanes, means for adjustably positioning the foregoing mechanisms within the air entry passageway for extension of the entry guide vanes within the rotor of a fan and beneath the fan blades thereof, and means for supporting said mechanism on the drive shaft 50 of the fan.
11. In a fan, the combination of a fan casing 55 having an air entry passageway, a fan rotor provided with blades spaced radially from the axis of the fan and axially disposed with respect to said passageway, and a disk-like damper movable inwardly and outwardly with respect to said inlet passageway having entry guide vanes associated therewith which are adapted to telescopically extend within the fan blade rotor to control the volume of air passing therethrough.
12. A new article of manufacture for use with 65 fans and adapted to regulate the quantity of air admitted to the fan without changing its efficiency, comprising a conical inlet damper plate having a plurality of longitudinally disposed guide vanes extending from the convex side thereof, said guide vanes being radially disposed with respect to said damper plate and of arcuate shape.

EDWARD L. ANDERSON.
